UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

RAILWAY CAR DROP DOOR

Original application filed April 25, 1929, Serial No. 358,008. Divided and this application filed June 7, 1930. Serial No. 459,688.

The invention relates to railway cars of the dumping type but more specifically to the so-called "general service" gondola cars wherein the floor consists of a plurality of doors, which doors usually have one end hinged to the center construction of the car and the other end supported by the side wall of the car when the door is in closed position. Such doors are usually each provided with a plurality of hinge elements and support elements, and I provide a beam element between each hinge element and its opposite supporting element. When two hinges are used to each door each of such beams supports substantially 50% of the load imposed upon the door and where three hinge elements are used each beam supports substantially one-third of the load imposed upon the door.

Such cars are provided with stops adjacent the sides of the door opening to restrict the downward movement of the door and the door is provided with bumpers to engage these stops. The stops are usually spaced to divide the length of the door into thirds according to known mechanical principles. I provide a beam element extending between the bumpers on the door which is substantially normal to the beam element extending between the hinge and supporting elements. When the door is dropped the load follows the door and at the moment of impact of the bumpers with the stops, this beam element carries substantially two-thirds of the load imposed upon the door. (See Fig. 2).

The object of this invention is to provide a hinged door for a railway car, which door is reinforced by beam elements which function when the door is in closed position and another beam element which functions when the door is in open position. Another object of the invention is to secure co-operation between these different beam elements whereby each beam element reinforces each other beam element.

In the drawings:

Figs. 1, 2 and 3 show a typical application of my invention to a railway car.

Figs. 4, 5 and 6 show a form of the door in detail.

Fig. 7 shows a modified construction.

Figs. 8, 9 and 10 are illustrative diagrams.

In the drawings the usual parts of the car are shown, such as center sills or center construction 1; cover plate 2; cross diaphragms 3; side wall 4; operating shaft 5; raising chain 6 and stop 7.

The door is provided with hinge elements 10 adjacent one end thereof which engage the hinges 11 mounted on the center construction 1. The door is also provided with support elements 12 adjacent the other end of the door to which the raising chain 6 is secured. The term "support element" means any means adjacent the outer end of the door which rests upon a part of the car proper to support the door when in a closed position. The door is further provided with a pair of spaced apart ribs 13 which preferably converge toward each other adjacent the hinge elements 10 and support elements 12, respectively. The two pairs of ribs forming the beam elements are so positioned as to divide the width of the door in substantially five equal parts. The bumpers 14 are preferably positioned adjacent the opposite sides of the door and another pair of spaced apart beam elements 15 extend between the oppositely disposed bumpers 14 which converge toward the bumpers. These last mentioned ribs 15 are preferably deeper than the ribs which extend between the hinge and support elements. The door is also provided with another rib 17 parallel to the last mentioned ribs, which together with the last mentioned ribs, are so positioned as to divide the length of the door into four substantially equal parts.

Fig. 7 shows a modified construction of the door wherein a plurality of minor (and preferably shallower) ribs 20-21 are provided parallel with each of the beam elements so as to provide relatively smaller unsupported areas in the door. The amount of ribbing and depth thereof would depend upon the size of the door and the load to be sustained.

If the doors are large it may be necessary to provide flanges adjacent each end and side margin of the door, in which case the ribs forming the beam elements could merge into these flanges.

As the ribs forming the beam element be-

tween the bumpers must support a greater load than the other beam elements they are preferably deeper so as to make them relatively stronger.

5 The different beam elements cross each other and are so formed as to prevent either one of them from deflecting under stress, thereby co-operating to strengthen each of them.

10 I prefer to make the door of cast metal wherein it is easier to distribute the metal in the door according to the stress imposed upon the various parts and a casting also eliminates fabrication and assembling of the 15 various parts, and furthermore, assures that the various parts of the door will remain intact and will not be loosened or severed by the motion of the train in service. The invention, however, is not limited to a cast metal door.

20 Figs. 8, 9 and 10 are diagrams wherein Fig. 8 shows the beam elements "a" extending between the hinge elements "b" and supports "c" and the other beam elements "d" extending 25 between the opposite bumpers "e". The shaded portion in Fig. 9 shows the area of the load supported by one of the beam elements "a" which is one-half of the load. The shaded portion in Fig. 10 shows the area of 30 the load supported by the beam "d" which is about two-thirds of the load, thus the beam "d" should be one-third stronger than the beam "a".

35 The accompanying drawings illustrate the preferred form of the invention, though it is to be understood that the invention is not limited to the exact details of construction shown and described, as it is obvious that various modifications thereof, within the 40 scope of the claims, will occur to persons skilled in the art.

This is a division of my co-pending application Serial No. 358,008, filed April 25, 1929.

I claim:

45 1. A door for a railway dump car comprising hinge elements adjacent one end thereof, support elements adjacent the other end thereof, bumpers adjacent the opposite sides thereof, a pair of spaced apart ribs extending between each of the hinge elements and the opposite support elements which converge toward the hinge elements and support elements, respectively, and another rib substantially normal to the first mentioned ribs 50 extending between said bumpers.

2. A door for a railway dump car comprising hinge elements adjacent one end thereof, support elements adjacent the other end thereof, bumpers adjacent the opposite sides 60 thereof, a pair of spaced apart ribs extending between each of the hinge elements and the opposite support elements which converge toward the hinge elements and support elements, respectively, and another pair of 65 spaced apart ribs substantially normal to the 70

first mentioned ribs extending between said bumpers which converge toward the bumpers.

3. A door for a railway dump car comprising hinge elements adjacent one end thereof, support elements adjacent the other end thereof, bumpers adjacent the opposite sides thereof, a pair of spaced apart ribs extending between each of the hinge elements and the opposite support elements which converge toward the hinge elements and support elements, respectively, and another rib substantially normal to the first mentioned ribs extending between said bumpers, and a plurality of ribs substantially parallel to the first mentioned ribs. 75 80

4. A door for a railway dump car comprising hinge elements adjacent one end thereof, support elements adjacent the other end thereof, bumpers adjacent the opposite sides thereof, a pair of spaced apart ribs extending between each of the hinge elements and the opposite support elements which converge toward the hinge elements and support elements, respectively, and another rib substantially normal to the first mentioned ribs extending between said bumpers, and a plurality of ribs substantially parallel to the first mentioned ribs, and a plurality of ribs substantially parallel to the rib extending between the bumpers. 85 90 95

5. In a railway car having a door opening and a door therefor, the combination of hinge members adjacent one end of the opening, support members adjacent the opposite end of the opening to support the door in closed position and door stops on the opposite sides of the opening to support the door in open position, said door provided with a pair of ribs extending between each hinge member and the opposite support member which converge toward the hinge member and support member, respectively, said door also provided with another pair of ribs extending between the portions of the door which engage said stops which converge toward said portions. 100 105 110
